UNITED STATES PATENT OFFICE.

JOHN VAN FLEET RYERSON, OF NEW BRUNSWICK, NEW JERSEY.

STATION-INDICATOR.

SPECIFICATION forming part of Letters Patent No. 267,941, dated November 21, 1882.

Application filed June 21, 1882. (No model.)

To all whom it may concern:

Be it known that I, JOHN V. F. RYERSON, of New Brunswick, in the county of Middlesex and State of New Jersey, have invented a new and useful Improvement in Station-Indicators for Railroad-Cars, Steamboats, and other Conveyances, of which the following is a full, clear, and exact description.

This invention relates to devices for indicating to passengers on railroad-cars and other conveyances, both on land and water, the names of the stations or stopping-places on the line of route as the conveyance approaches them, also preferably the terminal destination of the

w 15 conveyance. To these ends the invention comprises certain well-known elements, including rolls, on and from which webs having the names of the stations and destination marked on them are wound and unwound, to expose to view at the proper time the several stations successively and the ultimate destination of the conveyance; also, an alarm-bell or audible signal for calling the passengers' attention to the changes 25 made in the indicator when exposing to view the succeeding stations as they occur on the route.

The invention has more particularly reference to that class of such station-indicators in which the rolls that carry and operate the indicating-web are actuated automatically by one or more springs when released for the purpose, and in which an automatic stop mechanism is used for holding onto the one roll at 35 measured points in its rotation by the actuating-spring, for the purpose of exposing each succeeding station on the web; and the invention consists in certain novel combinations of parts or devices in such apparatus, including 40 a lever-stop mechanism of special construction, substantially as hereinafter described, whereby great simplicity and efficiency are obtained.

Reference is to be had to the accompanying drawings, forming part of this specification, in 45 which similar letters of reference indicate corresponding parts in all the figures.

Figure 1 represents a plan of a train of railroad-cars in part, with my improved indicators arranged at the ends of the cars, and showing 50 a full rope for operating them conjointly throughout the several cars. Fig. 2 is a partly-broken front view, upon a larger scale, of one

of the indicators with the front frame-piece of its case removed; Fig. 3, a vertical transverse section on the line *xx* in Fig. 2; Fig. 4, a further like section on the line *yy* in Fig. 2; and Fig. 5, a vertical transverse section of a modified construction of the indicator as hereinafter described. Fig. 6 is a longitudinal section, on the line *zz* in Fig. 3, of one of the 60 spring-rolls used in the indicator, and which corresponds with the other spring-rolls employed in the device.

Referring in the first instance to Figs. 1, 2, 3, 4, and 6 of the drawings, A A indicate the cars of a railroad-train, and B B the station-indicators, arranged at an elevated position in both ends of the cars and actuated synchronously throughout the train by a pull-rope, C, under the control of the engineer, conductor, or other authorized person. Said pull-rope, which is in sections corresponding with the number of cars, should be provided with suitable couplings for connecting said sections when coupling the cars together, and with 70 springs *b*, or take-ups, for preventing slack and insuring like action of the several indicators.

The connection of the pull-rope C with the several indicators may be made by branch cords *d*, each of which is attached at its one 80 end to the pull-rope and passes between guides or pulleys *e e* and over a pulley, *f*, down to the holder D of the indicator under control by it. By this arrangement the pull-rope C may be drawn in reverse directions to actuate the 85 indicators, the convenience of which as regards the run of the cars on opposite tracks, or as regards working them from opposite ends of the train, will be readily understood. Such operating devices, however, may be changed, 90 or each indicator may be operated separately by an independent "pull," or the several indicators throughout a train may be actuated by electrical means, by steam-power from the engine, or by compressed air.

Each indicator, when single—that is, when organized to be viewed only from its one side or front *g*, which has glazed openings *h h* in it—is constructed substantially as follows:

E is the web or strip of flexible material, upon 100 which the stations on the route are indicated at suitable distances apart, and which is secured at its opposite ends to the rolls F G, so that when unwound from the one roll it is

wound onto the other, and the web is exposed to view in front of the rolls. One of these rolls, F, is a spring one, similar to the one, M, shown in Fig. 6, being made hollow, with one 5 or more springs, *i*, extending through it and attached to a winding-spindle, *k*, and the body of the roll, subject to the control of a locking device, so that when the holder D, which engages with the other roll, G, is released, the 10 web E is drawn from off the roll, G, onto the spring-roll F by the action of its governing-spring to expose the stations on the web successively to view. This holder D is a toothed lever, pivoted at *l* to the case, and engages in 15 succession with two or more teeth, *m*, on the roll G. It is here shown as engaging successively with two oppositely-arranged teeth, *m*, which measure the travel of the web to change the exposure of the succeeding stations on it 20 to view, each half-revolution of the roll G exposing the name of a succeeding station on the web.

The holder D is dropped by a spring connecting at its free end *l* with a gong-bell, to 25 engage with the roll G, and is released by drawing in either direction on the pull-rope C. When in engagement with the roll G it holds tripped or supported from engagement with said roll a stop, H, controlled by a spring, *p*, 30 which is pivoted at *n* to the outside case, and has a side tripping-pin, *o*, extending under the holder, by which it is raised and released by said holder from engagement with the roll G; but when the holder D is released from hold 35 on the roll G it allows the stop H to drop and engage with the succeeding tooth *m* until the holder D is readjusted by relinquishing hold on the pull-rope to engage with said succeeding tooth. Thus, no matter how long the 40 pull may be retained on the rope C, the spring-roll F is prevented by the lock of the stop H with the roll G from taking up any more of the web E than is necessary to expose a succeeding station.

45 When the spring of the roll F has run out it may be rewound by a key applied to turn the roll G and set in motion the web E for the purpose. When additional spring-power is required to take up more web the roll F should 50 be locked and the spring in said roll be wound up by a key fitting the end of its spindle.

I J are plain rolls carrying a web, K, on which the different terminal destinations of the route are printed, and which may be 55 changed by hand or key applied to either of said rolls.

S is a bell or alarm, which, by suitable connections, is sounded every time the station-indicator B is operated to call the attention of 60 the passengers to the change made on the indicator.

All of the rolls F G and I J, or either pair, may be made interchangeable with others to suit variations in or extensions or curtailments of the route, and for this purpose they should 65 be so fitted to the case of the indicator and said case be so constructed with one or more lids or doors as readily to admit of this.

When necessary to indicate a "flag-station" 70 the web E may have a star on it opposite said station thereon, and a notice be appended to the case signifying that the exposure of a star has such meaning.

M is an automatic catch spring-roll similar to the window-shade rolls in use, on which is 75 wound a web or drop, N, that is drawn down or exposed before a station is reached, and has printed on it a caution for passengers to keep their seats till the train stops, or which may have delineated on it any other cautionary no- 80 tice.

Instead of arranging the station-indicators B at the end of the cars, they may be arranged in the centers thereof and be made double, as shown in Fig. 5—that is, with the web E ex- 85 posed to view on both of its sides through op- 90 posite glazed openings *h*, and said web have the stations marked on both of its sides. In this case both rolls carrying said web should be spring-rolls with their springs wound in op- 95 posite direction, and with a bolt applied to the arbor of either one to lock it, according to the direction in which the train is running and the web requires to move, while the other of said rolls is controlled by a holder, D, and stop H, as hereinbefore described.

If desired, instead of the pull-rope C, with its branches *d*, being used for releasing the holders D, a pull-rope arranged to run over suitable pulleys and carrying movable pulleys con- 100 nected with said holders may be employed.

Having thus described my invention, what I claim as new, and desire to secure by Letters Patent, is—

1. The combination of the spring-roller F, 105 the roller G, having teeth *m*, the station-indicating web E, the toothed pivoted holder D, controlled by a pull-rope or device for releasing the same, and the stop H, having a fixed pivot, *n*, and provided with a tripping pin or 110 projection, *o*, for operation by the holder, es- sentially as described.

2. The pull-rope C, with its attached branches *d*, in combination with the guides *e*, the pulleys *f*, the pivoted holders D, the lever- 115 stops H, tripped by the holders, and the roll G of the indicator, having teeth *m*, substan- tially as specified.

JOHN V. F. RYERSON.
